Primary Examiner — Darlington Ly*(74) Attorney, Agent, or Firm* — Polson Intellectual Property Law, PC; Margaret Polson(57) **CLAIM**

The ornamental design for a grill, as shown and described.

DESCRIPTION

FIG. 1 is a front and left side perspective view of a grill showing my new design;

FIG. 2 is a rear and left side perspective view thereof;

FIG. 3 is a top plan view thereof;

FIG. 4 is a front elevation view thereof; and,

FIG. 5 is a right side elevation view thereof, of which the opposing left side elevation view a mirror image.

The broken lines in the drawings illustrate portions of the grill that form no part of the claimed design.

1 Claim, 5 Drawing Sheets(56)
